UNITED STATES PATENT OFFICE.

CHARLES H. MULRONEY, OF CLEVELAND, OHIO.

TOOTH FOR SHOVEL-DIPPERS.

1,363,189.

Specification of Letters Patent. Patented Dec. 21, 1920.

Application filed October 10, 1917. Serial No. 195,834.

To all whom it may concern:

Be it known that I, CHARLES H. MULRONEY, a citizen of the United States, and a resident of Cleveland, in the county of Cuyahoga and State of Ohio, have invented 5 a new and Improved Tooth for Shovel-Dippers, of which the following is a full, clear, and exact description.

My invention has for its objects to provide a tooth for shovel dippers having a base with a detachable wearing plate at its bottom and a detachable point at the front of the tooth. The point has a rearward projection fitting a cavity or recess in the base, and the base has a forward projection fitting a cavity or recess in the point. The point also has a boss extending upwardly from a rearwardly extending foot, the boss being disposed in a recess in the 10 bottom of the base, there being an opening in the base which extends upwardly and rearwardly from the recess in its bottom and which registers with an opening which extends through the boss so that a bolt may be disposed through the openings to secure the foot of the point to the base. The wearing plate has tenons at its sides which fit in grooves at the sides of the bottom of the base, and bosses which fit in recesses in the 15 bottom of the base, there being openings through the bosses which register with openings in the base and through which bolts are disposed to secure the wearing plate in position.

Additional objects of the invention will appear in the following specification, in which the preferred form of my invention will be described.

In the drawings similar reference characters refer to similar parts in all the views, in which—

Figure 1 is a side elevation of my tooth showing the manner in which it is secured to the shovel which is illustrated in section, 45 Fig. 2 is a side elevation of the pointed tooth,

Fig. 3 is a fragmentary view illustrating the forward portion of the base,

Fig. 4 is a sectional view on the line 4—4 50 of Fig. 1,

Fig. 5 is a sectional view on the line 5—5 of Fig. 1, and

Fig. 6 is a plan view of the wearing plate.

By referring to the drawings, it will be seen that the tooth is provided with a base

10, a detachable point 11 and a wearing plate 12. At the front of the base 10, there is a cavity or recess 13 which extends rearwardly and downwardly, and below the 60 recess or cavity 11, the base 10 has a projection 14 which is spaced from the sides of the base. This projection 14 is disposed in a recess or cavity 15 at the rear of the point 11, and a downwardly and rearwardly extending projection 16 on the point 11 is normally disposed in the recess 13. By this construction, the base 10 obtains a firm grip on the point 11 and there is no danger of the point 11 wearing loose 65 in operation.

The point 11 has a rearwardly extending shoe 17 which is disposed under the base 10 as illustrated in Fig. 1 in the drawings, this shoe 17 having a boss 18 which extends 75 upwardly and rearwardly and which normally fits in a recess 19 in the bottom of the base 10. There is an upwardly and rearwardly extending opening 20 from the bottom of the shoe 17 through the boss 18. 80 This opening 20 registers with an opening 21 in the base 10, so that a bolt 22 may be disposed through the openings 20 and 21 to hold the shoe 17 in position and prevent the projections 14 and 16 from working 85 out of the recesses or cavities in which they are normally disposed.

At the rear of the shoe 17 and at the bottom of the base 10, the wearing plate 12 is disposed, it being possible to renew the point 90 11 without disturbing the wearing plate, but nevertheless, when desired, the wearing plate 12 may be replaced. This wearing plate 12 has tenons 23 at its sides which connect with a transverse tenon 24 at the front of the 95 wearing plate 12; the tenons 23 being normally disposed in grooves 25 at the sides of the bottom of the base 10, and the transverse tenon 24 being disposed in a transverse groove which connects the said grooves 25 at 100 the front of the wearing plate 12. The wearing plate 12 is also provided with bosses 26 which are disposed in recesses 27 in the bottom of the base 10, there being openings 28 through the bosses 26 which register with 105 openings 29 in the base 10, so that bolts 30 may be disposed through the said openings 28 and 29 to secure the wearing plate 12 to the base. These bolts 30 not only serve to secure the wearing plate 10 to the base, but they 110 are also disposed through openings 31 at the front 32 of the shovel; the said shovel por-

tion 32 being disposed in a longitudinal extending slot 33 in the base 10.

The point 11 is secured to the base 10 by 5 tilting the outer end of the point 11 upwardly, so that the projection 16 may be disposed downwardly and rearwardly in the recess 13. It is then possible to rotate the front of the point 11 downwardly and rearwardly to move the projection 16 home in 10 the curved recess 13 and to move the projection 14 into and home in the recess 15. With this rotary movement of the point 11, the shoe 17 will be moved into position against the bottom of the base 10. It will be understood 15 that the boss 18 may be rounded as may be necessary to obtain a close fit between the parts. As the projection 16 is curved downwardly and rearwardly, the harder the work of the tooth on the upward stroke, the tighter 20 the point will be held by the boss. It will be seen that when the shovel is making a working or upward stroke, there is no strain on the bolt 22 and when the shovel is moved downwardly, the action on the bolt is a direct 25 longitudinal pull.

I claim:

1. In a tooth for shovel dippers, a base member having a forward surface, a point member having a rear surface, and a rearwardly extending shoe, a curved projection extending from one surface, there being a curved recess in the other surface for receiving the curved projection so that the point member may be rotated downwardly 30 and rearwardly to lock the curved projection in the curved recess and to bring the shoe against the bottom of the base member, there being an opening in the base member extending from the bottom thereof upwardly 35 and rearwardly, and there being an opening in the shoe registering with the said opening in the base, and a bolt extending through the openings.

2. In a tooth for shovel dippers, a base 45 having a bottom and an opening extending upwardly and rearwardly therethrough from its bottom, a point disposed at the front of the base and having a shoe extending rearwardly along the bottom of the base 50 beyond said opening, locking means at the front of the base for locking the point in place relative to the base, there being an opening in the shoe registering with the opening in the base, and a bolt extending 55 through the openings, for the purpose specified.

3. In a tooth for shovel dippers, a base having a recess at its bottom and an opening extending upwardly and rearwardly 60 through the base from the recess, a point disposed at the front of the base and having a foot extending rearwardly along said base beyond said opening, a boss on the foot of the point normally disposed in the recess, 65 means at the front of the base engaging the

point for holding the latter in place, there being an opening extending through said boss and registering with the opening through the base, and a bolt extending through the openings, for the purpose specified. 70

4. In a tooth for shovel dippers, a base having a curved recess in its forward end, said recess extending downwardly and rearwardly into said base, a point abutting against the forward end of said base and having a curved projection extending downwardly and rearwardly from its said abutting surface, for fitting the recess in the base, a rearwardly extending shoe at the bottom 80 of the point extending along the bottom of the base, and means for securing said shoe to said base. 85

5. In a tooth for shovel dippers, a base member having a curved recess in its forward end, said recess extending downwardly and rearwardly into said base, a projection extending forwardly from said base below its recess, a point member having a curved projection extending rearwardly and downwardly therefrom for disposal in the recess in the base member, the point member being provided with a recess below its projection adapted to receive the projection extending forwardly from said base, a shoe 95 extending rearwardly from the bottom of the point member and disposed under the base member, and means for securing the shoe to the base member. 90

6. In a tooth for shovel dippers, a base member having a curved recess in its forward end, said recess extending downwardly and rearwardly into said base, a projection extending forwardly from said base below its recess, a point member having a curved 100 projection extending rearwardly and downwardly therefrom for disposal in the recess in the base member, the point member being provided with a recess below its projection adapted to receive the projection extending forwardly from said base, a shoe 110 extending rearwardly from the bottom of the point member and disposed under the base member, there being an opening extending from the bottom of the base member upwardly and rearwardly therethrough, there being an opening through the shoe registering with said opening through the base member, and a bolt extending through the openings, for 115 the purpose specified. 120

7. In a tooth for shovel dippers, a base member, a point member fitting on the base member, the said members being provided one with a curved projection and the other with a curved recess for receiving the projection, the said projection and recess extending downwardly and rearwardly, permitting rotation of the point member downwardly and rearwardly relative to the base member, a shoe extending rearwardly from 130

the bottom of the point member, and means for securing the shoe to the bottom of the base member.

8. In a tooth for shovel dippers, a point having a recess in its rear surface and a projection extending rearwardly from above the recess, a base having a projection extending forwardly therefrom for disposal in the recess in the point, and a recess above the 10 said projection for receiving the projection on the point, the point having a shoe at its bottom extending the base, there being an opening extending from the bottom of the base upwardly and rearwardly through the 15 base, there being an opening through the shoe which registers with the opening in the base, and a bolt extending through the openings.

9. In a tooth for shovel dippers, a base 20 having a bottom with grooves at its sides, there being a recess in the bottom between the sides and there being an opening through the base extending upwardly from the recess, a wearing plate disposed at the bottom 25 of the base and having tenons disposed in the grooves, a boss on the wearing plate disposed in the recess, there being an opening through the boss which registers with the opening in the base, and a bolt extending 30 through the openings.

10. In a tooth for shovel dippers, a base

having a bottom with grooves at its sides, there being a recess in the bottom between the sides and there being an opening through the base extending upwardly from the recess, a wearing plate disposed at the bottom 35 of the base and having tenons disposed in the grooves, a boss on the wearing plate disposed in the recess, there being an opening through the boss which registers with the 40 opening in the base, a bolt extending through the openings, a point disposed at the front of the base and having a shoe extending rearwardly therefrom under the base and disposed adjacent the wearing plate, and 45 means to detachably secure the point to the base.

11. In a tooth for shovel dippers, a point having a concave rear surface and a curved recess in said surface, a curved projection extending rearwardly and downwardly from said surface of the point, a base having a convex front end with a curved recess therein for receiving the curved projection on the point, a curved projection extending forwardly from the base for disposal in the curved recess in the point, and means for securing the bottom of the point to the bottom of the base for maintaining engagement 50 of said projections in said recesses. 55

CHARLES H. MULRONEY.
